UNITED STATES PATENT OFFICE

1,926,355

MARKING MACHINE

Perle E. Tarlton, Los Angeles, Calif.

Application July 8, 1931. Serial No. 549,354

14 Claims. (Cl. 101—336)

My invention relates to machines for delineating upon objects, particularly fruit, a suitable indicium or suitable indicia and is more especially related to electric fruit marking machines 5 of the general type shown in the United States Letters Patent Number 1,421,292 issued to Louis Neuenschwander and of the general type disclosed in my Patent Number 1,658,468 issued February 7th, 1928.

10 In such machines there is provided an electrically heated die adapted to engage with an object to be marked, such as a fruit, to impress or delineate upon the fruit an indicium corresponding to the configuration of the die. In marking some objects it is desirable to apply ink to the die prior to the marking operation and although an inking ribbon has heretofore been used for this purpose it has not been satisfactorily fed nor does it have a sufficiently long 20 life.

It is, therefore, an object of my invention to provide a marking machine in which there is utilized an inking ribbon capable of extensive re-use.

25 Another object of my invention is to provide a marking machine in which the inking ribbon affords a uniformity of result.

An additional object of my invention is to provide a marking machine in which the inking ribbon is fed uniformly to the die.

A further object of my invention is in general to improve marking machines of the type disclosed in the above-mentioned patents.

The foregoing and other objects are attained 35 in the embodiment of the invention shown in the drawings, in which

Figure 1 is a side elevation of a marking machine constructed in accordance with my invention, particularly showing the inking mechanism in association with so much of the remainder of the marking machine as will serve to identify the shown part in my above mentioned patent.

40 Figure 2 is a side elevation of a portion of the ribbon advancing mechanism.

Figure 3 is a cross section, the plane of which is indicated by the line 3—3 of Figure 4.

Fig. 4 is an end elevational view of the marking machine.

45 Figure 5 is a cross section, the plane of which is indicated by the line 5—5 of Figure 1.

Figure 6 is an end elevation of the pawl engaging the ratchet wheel with the pad arm shown 50 in longitudinal cross section.

Figure 7 is a cross section on the line 7—7 of Figure 6.

Figure 8 is a cross section on the line 8—8 of Figure 1.

Figure 9 is a cross section on the line 9—9 of 60 Figure 8.

In its preferred form, the marking machine of my invention comprises a die together with a ribbon located adjacent the die and adapted to contact the die to effect an inking operation 65 incorporated with means for advancing the ribbon a predetermined amount for each inking operation.

As particularly shown in Figure 1, the marking machine includes a shaft 6 carrying a disc 70 having a plurality of dies 7 at the periphery thereof. Each of the dies is a relatively planar structure provided with indicia 8 thereon in relief. In the operation of the machine the shaft 6 rotates in order to contact the successive dies 75 with fruit or other objects to be marked, as indicated in my above identified patent.

In the present instance it is deemed advisable to provide each die 7 with ink prior to the marking operation and to this end I preferably situate 80 adjacent the die 7 a pad arm 9 which, at one end is loosely mounted on a shaft 11 carried by the framework of the machine, not shown, and at the other end is enlarged to receive a pad 12 of any suitable character usually made up of 85 resilient material such as alternate layers of rubber and cork. The pad 12 is adapted to abut or substantially to abut whichever one of the dies 7 is in suitable position therefor. In order to urge the pad arm 9 resiliently toward the 90 die 7, I likewise fix on the shaft 11 by any suitable means such as a set screw 13, a crank arm 14 which is secured to an eccentric strap 16 encompassing an eccentric 17 driven by a shaft 18. The shaft 18 is synchronized with the movement 95 of the shaft 6 in accordance with the disclosure of my co-pending application entitled Fruit marking machine, filed July 8, 1931 with Serial No. 549,355. That is, for each step of advancement of the shaft 6 to bring a successive die 7 into lowermost position, as shown in Figure 4, the shaft 18 makes one complete revolution and therefore reciprocates the arm 14 through one cycle.

In order that the movement of the arm 14 may 105 be resiliently effective upon the pad arm 9, I preferably mount on the shaft 11 to move therewith a frame 21 usually of cast metal which is provided with a receptacle 22 to receive a coil spring 23 the other end of which abuts the under 110

side of the pad arm 9. The frame 21 likewise carries a stop pin 24 for limiting the relative movement of the pad arm and the frame 21. During the rotation of the eccentric 17 the frame 21 reciprocates in unison with the reciprocation of the arm 14 and through the spring 23 resiliently urges the pad arm 9 toward the die 7. When the pad arm or the pad 12 encounters a superior resistance, the spring 23 is compressed to permit completion of the cycle of the eccentric 17. Return movement by virtue of continued rotation of the eccentric permits the pad arm 9 to move away from the die 7 and permits the spring 23 to expand forcing the pad arm 9 against the stop pin 24. For each step of advancement of the shaft 6 the pad arm and pad 12 approach and recede from the lowermost die 7.

In order that ink may be deposited on each die 7 I preferably provide an inking ribbon 26 which preferably at one end is wound upon a reel 27 mounted on a pin 28 fastened to a standard 29 forming part of the machine framework and at the other end is wound on a reel 31 carried by a spool 32 rotatably mounted on a stud 33 projecting from an upright 34 forming part of the machine framework. The ribbon 26 is spirally wound upon each of the spools and is adapted to be transferred from one spool to the other spool. Initially a full spool of ribbon is placed on the stud 28 and is threaded over a support arm 36 extending from the upright 29 and carrying a suitable guide 37. The ribbon then extends around a similar guide 38 on an upright 39 of the frame 34 and terminates on the spool 31 having passed between the pad 12 and the die 7 or in other words, being interposed therebetween. In order to place a tension on the ribbon 26 and to prevent unwarranted rotation of the reel 27 I preferably provide a brake including a lever 41 pivoted as at 112 to the upright 29 and carrying guide ears 43 for ensuring alignment of the ribbon and likewise a projection 44 to furnish additional weight.

Since I preferably advance the ribbon 26 in accordance with the movement of the arm 9 or substantially in accordance therewith I preferably provide the frame 21 with a pair of depending ears 46 pierced by a pivot pin 47. Depending from and rotatably mounted on the pivot pin 47 is a block 48 transversely pierced to carry a pin 49 on which a pawl 51 is mounted. Preferably, the pawl is fabricated of a metal sheet suitably formed to provide at its lower extremity a pair of guide ears 52 and a tooth 53 while at its upper end is located an extension 54 for abutment against a coil spring 56 seated in a cavity 57 in the block 48 to urge the tooth 53 into contact with a ratchet wheel 58. The ratchet wheel 58 is mounted on a shaft 59 journalled in the upright 34 which likewise carries a guide 60 adjustably mounted as at 62 so that initial movement of the pawl 51 causes the tooth to ride over the guide 60 and after leaving the guide to be pressed into engagement with the teeth of the ratchet wheel 58. By suitably adjusting the guide 60 the amount of advancement of the ratchet wheel 58 for each cycle of movement of the pawl 51 can be regulated.

Retrograde movement of the ratchet wheel is prevented by a spring pressed pawl 61.

Mounted on the shaft 59, which is rotated by the ratchet wheel 58, is an eccentric 63 contacted by a reciprocating yoke 64 pivoted as at 66 on the uprights 34 and having a pair of ex-

tending arms 67 and 68, the latter of which is pierced by a plurality of apertures 69, 71 and 72. As the frame 21 reciprocates by virtue of the action of the eccentric 17 the pawl 51 intermittently advances the ratchet wheel 58 the desired amount and rotates the eccentric 63 so that the yoke 64 is likewise reciprocated. A connecting bar 73 is provided at one end with a pin 74 adapted to be seated in any one of the apertures 69, 71 or 72 and at its other end is provided with a pin 76 adapted to be located in any one of several apertures 77 in a lever 78 mounted on a shaft 79 piercing and journalled in the upright 34. To assist in holding the bar 73 in adjusted position a leaf spring 81 is fastened as at 82 to the bar and is provided with free ends abutting the arms 68 and 78. By suitably disposing the connecting bar 73 the ratio of angular movement between the yoke 64 and the arm 78 may be adjusted as desired to give the requisite oscillation to the shaft 79.

The shaft 79 in emerging from the opposite side of the upright 34 forms a mounting for a lever 83 at its lower end carrying a fork 84 held by a pivot pin 86. The fork at its free extremity is provided with a tine 87 which is enlarged to bear against the roll of ribbon 26 on the reel 31 and with a tine 88 which carries pivotally a friction finger 89 having a curved cam surface 91 adapted to contact and engage frictionally one of the flanges 92 of the reel 32. The finger 89 is urged by a coil spring 93 to rotate so that its cam surface 91 is in tight engagement with the flange 92. A pin 94 on the tine 88 serves as a stop for the finger 89. The entire fork 84 is urged to cause the tine 87 to contact the ribbon on the reel 31 by a coil spring 95 the upper end of which is fastened to a bracket 96 carried by the upright 34. Preferably the periphery of the other flange 97 of the reel 32 is provided with a succession of serrations or notches 98 which are engaged by a pawl 99 pivoted as at 101 to the upright 34 and urged into contact with the serrations by a coil spring 102 secured to the upright 34. Fastened to the pawl 99 is a follower 103 lying between the flanges 92 and 97 in the path of ribbon winding spirally upon the reel 31.

As the shaft 79 is oscillated the arm 83 is likewise reciprocated causing the fork 84 to advance and retreat with respect to the flange 92. The reel 31 being rotatably mounted, advancing movement of the fork 84 causes the finger 89 to slide over the flange 92, since the frictional engagement of these parts tends to cause retrograde movement of the flange 92 and the flange 97 which is impossible by virtue of the pawl 99. However, the spring 93 is sufficiently resilient to permit the finger 89 to rock slightly about its pivotal point and reduce the friction between the finger and the flange 92. Upon retreating movement of the arm 83 and return of the fork 84 toward its original position, the spring 93 urges the finger 89 into tight frictional engagement between the surface 91 and the flange 92 so that these two parts are in effect locked together and since there is no hindrance by the pawl 99 the flange 92 and in fact the entire reel 31 are rotated thus advancing the ribbon 26. Since the fork 87 follows the surface of the ribbon being wound spirally upon the reel 31, equal movement of the fork 84 causes an equal amount or a predetermined amount of ribbon 26 to be wound upon the reel 31 each cycle despite the diameter of the ribbon 150

on the reel. Although the ribbon is advanced at a constant rate, the energizing movement is not imparted to the ratchet wheel 58 during the time the pad arm 9 approaches the die 7 and the ribbon 26 is stationary during its contact with the die 7.

The ribbon is thus advanced from the spool 27 toward the spool 31 until such time as the ribbon on the spool 31 abuts the follower 103 and lifts the pawl 99 out of engagement with the serrations 97. Since the pawl does not then make mandatory a relative sliding movement between the finger 89 and the flange 92, the finger is substantially locked thereto for both directions of movement of the fork 84 and the reel 31 is oscillated between relatively narrow limits without advancing the ribbon. The full reel of ribbon can easily be removed by suitably operating a lever 106 which withdraws a pin 107 against the urgency of a spring 108 and provides a free passage for removal of the reel 32.

It is to be understood that I do not limit myself to the form of the marking machine shown and described herein, as the invention, as set forth in the following claims may be embodied in a plurality of forms.

I claim:

1. In a marking machine, a die, a ribbon adjacent said die, a reel for advancing said ribbon with respect to said die, a reciprocable pad arm for effecting contact of said ribbon and said die, and means connected to said pad arm for actuating said reel to advance said ribbon at a constant rate.
2. In a marking machine, a die, a ribbon adjacent said die, a reel for advancing said ribbon with respect to said die, a reciprocable pad arm for effecting contact of said ribbon and said die, and means connected to said pad arm for actuating said reel to advance said ribbon intermittently at a constant rate.
3. In a marking machine, a die, a ribbon adjacent said die, a reel for advancing said ribbon with respect to said die, and a pad arm adapted alternately to effect contact of said ribbon and said die and to advance said ribbon at a constant rate.
4. In a marking machine, a die, a ribbon adjacent said die, a reel for advancing said ribbon with respect to said die, and a pad arm adapted intermittently to effect contact of said ribbon and said die and to advance said ribbon at a constant rate.
5. In a marking machine, a die, a ribbon adjacent said die, means for periodically effecting contact of said ribbon and said die, and means for advancing said ribbon at a constant rate past said die when said ribbon is out of contact with said die.
6. In a marking machine, a die, a ribbon, means for periodically effecting an inking operation by mutually contacting said ribbon and

said die, and means for advancing said ribbon at a constant rate for each inking operation.

7. In a marking machine, a die, a pair of reels, a ribbon connected to both of said reels and disposed adjacent said die, means for effecting an inking operation by mutually contacting said ribbon and said die, and means engaging one of said reels for advancing said ribbon at a constant rate for said inking operation.

8. In a marking machine, a pad mounted for movement, a reel, a ribbon connected to said reel and disposed adjacent said pad, means for moving said pad to contact said ribbon for effecting an inking operation, and means connected to said pad arm for advancing said ribbon at a constant rate for said inking operation.

9. In a marking machine, a pivoted pad arm, means for periodically moving said arm, a pad on said arm, a ribbon adjacent said pad and adapted to be periodically contacted by said pad to effect inking operations, and means connected to said pad arm for advancing said ribbon at a constant rate for each inking operation.

10. In a marking machine, a die, a pivoted pad arm, means for periodically moving said pad arm toward and away from said die, a ribbon interposed between said die and said pad arm, and means for advancing said ribbon at a constant rate for each cycle of movement of said pad arm.

11. In a marking machine, a die, a pivoted pad arm, means for periodically moving said pad arm toward and away from said die, a ribbon interposed between said die and said pad arm, and means for advancing said ribbon at a constant rate for each movement of said pad arm away from said die.

12. In a marking machine, a die, an inking ribbon, a reciprocable pad arm for pressing said ribbon against the die, ribbon advancing means, and means moving in time with reciprocation of the pad arm for actuating said ribbon advancing means to advance the ribbon a predetermined equal amount for each reciprocation of the pad arm.

13. In a marking machine, a die, a reciprocable pad arm for pressing an inking ribbon against said die, a ribbon reel, means rotated in time with the reciprocation of said pad arm, and reciprocating means engaging said ribbon reel for advancing said ribbon a predetermined equal amount for each rotation of said rotated means.

14. In a marking machine, a die, a pad arm adapted to reciprocate toward and away from said die, a pad on said pad arm, a pair of reels, a ribbon engaging said reels and interposed between said die and said pad, a ratchet wheel, a pawl on said pad arm engaging said ratchet wheel, and a reciprocating arm engaging one of said reels and driven by said ratchet wheel.

PERLE E. TARTON.
